UNITED STATES PATENT OFFICE.

LOYAL W. SHERIDAN, OF MEDIAPOLIS, IOWA.

INTERNAL-COMBUSTION ENGINE.

1,140,489.

Specification of Letters Patent. Patented May 25, 1915.

Application filed November 7, 1912. Serial No. 730,015.

To all whom it may concern:

Be it known that I, LOYAL W. SHERIDAN, a citizen of the United States, residing at Mediapolis, in the county of Des Moines and State of Iowa, have invented new and useful Improvements in Internal-Combustion Engines, of which the following is a specification.

My present invention relates to internal combustion engines, and more particularly to revoluble valve means for controlling the intake and exhaust ports of the cylinder or cylinders thereof, driven from a common shaft by mechanism operable at a positive velocity ratio from the engine drive shaft.

The principal object of my invention is to simplify the valve mechanism and provide means for the opening and closing of the intake and exhaust ports by positive mechanism, or in other words, without the aid of springs, or the suction and compression provided by the reciprocation of a piston or pistons of the engine.

The invention is applicable to engines of the single or multiple cylinder type, and in both cases, the exhaust and intake ports of the cylinder or cylinders, are controlled by valves movable with a shaft common to all.

Other objects of my invention will appear in the following detailed description, taken in connection with the accompanying drawing, forming a part of this specification, and in which drawing:

Figure 1 is an end elevation of an engine embodying my invention, a part being broken away to disclose details. Fig. 2 is a view similar to Fig. 1 viewing the engine from the other end thereof. Fig. 3 is a sectional view on the line 3—3 of Fig. 1.

In the drawing where similar characters refer to similar parts, 4 designates engine cylinders, of the type having the usual trunk pistons indicated at 5, connecting rods indicated at 6, and operatively connected with

45 a crank shaft 7.

The explosion space 8 is provided, in part, by two oppositely disposed wall portions, preferably having parallel outer plane faces, and when a plurality of cylinders are provided, all the exterior faces of these wall portions 9 are preferably in parallelism.

The wall portions 9 of each cylinder have intake and exhaust ports 10 and 11 for the cylinder 4, these ports opening one at the exterior face of each of said wall portions. In facial contact with the said outer faces of

each wall portion having an intake port, is a revoluble disk valve 12, and similarly each wall portion having an exhaust port has a revoluble disk valve 13. All of the disk valves are mounted on a common shaft 14 received by suitable bearings 15, this shaft being disposed with its axis substantially parallel to the axis of drive shaft 7, from which it is driven at a positive velocity ratio, as by sprockets 16 and 17, and chain 18, the former sprocket being rigid with shaft 14, and the latter rigid with shaft 7.

The valves 12 and 13 are provided with suitable casings 19 and 20, respectively, so that fluid may be conveyed to or from contact with said valves at the faces thereof opposite from that in contact with the outer faces of wall portions 9.

When a multiple cylinder engine is equipped with valve means constructed according to my invention, ducts 21 may lead from casings 19 to a manifold 22, and from the casings 20, ducts 23 to a manifold 24.

Referring now more particularly to Fig. 80 1 of the drawing, it is to be noted that valve 13 has a transverse way 25 disposed with reference to the axis of rotation of said valve, so that said way opens to port 11 during a phase of movement of the valve, and 85 provides for exhaust of the waste products of combustion into casing 20. In this view the piston 5, is shown as having completed its exhaust stroke and is ready to move for intake of fuel.

With particular reference to Fig. 2 of the drawing, the engine piston is disclosed as being in the same position as described in connection with Fig. 1, and it is to be noted that valve 12 has a transverse way 26 disposed, with reference to the axis of rotation thereof, so as to open to port 10 during a phase of movement of valve 12, so that a way is provided for intake of fuel from casing 19.

The disk valves 12 and 13 may be secured to shaft 14 in any suitable manner, permanently or adjustably, and the casings 19 and 20 may be built up in any suitable manner, consistent with their function as conduits 105 or ways for conducting fluid. Furthermore, the valves 12 and 13 may have a plurality of ways disposed equi-distant from the axis of rotation so long as the velocity ratio of shafts 7 and 14 is such as to open the intake and exhaust ports synchronously with the intake and exhaust strokes, respectively, of

the engine pistons, and close such ports during the compression and power strokes thereof.

From the foregoing it is made manifest that I provide port controlled mechanism for internal combustion engines, which is simple in construction, efficient in action, and well adapted for successful operation without the use of springs or dependent upon suction or compression in the cylinder or cylinders.

Changes in details may be made without departing from the spirit or scope of my invention; but,

15 I claim:

1. In an internal combustion engine, the combination with the drive shaft thereof, of a second shaft parallel thereto and abutting the combustion chambers of the cylinders of said engine, intake disk valves for each cylinder provided with intake ports, a portion of each of said valves abutting its respective combustion chamber, the latter being provided with intake ports for intermittent registration with first said ports, a casing surrounding each of said valves and spaced therefrom to permit of the passage of a fluid thereabout, and manifold ducts similarly connecting said intake casings.
- 20 2. In an internal combustion engine, the combination with the drive shaft thereof, of a second shaft parallel thereto and abutting the combustion chambers of the cylinders of

said engine, exhaust disk valves for each cylinder provided with exhaust ports, a portion of each of said valves abutting its respective combustion chamber, the latter being provided with exhaust ports for intermittent registration with first said ports, a casing surrounding each of said valves and spaced therefrom to permit of the passage of a fluid thereabout, and manifold ducts similarly connecting said exhaust casings.

3. In an internal combustion engine, the combination with the drive shaft thereof, of a plurality of cylinders, each having two plane faces in parallelism to which the intake and exhaust ports open, the said faces of all of said cylinders being in parallelism; a second shaft having its axis parallel to the axis of said drive shaft; a plurality of valves, rotatable with said second shaft, one for each port of said cylinders, and each having a transverse way to open to its respective port during a predetermined period of rotation of said shaft; a way about the face of each valve opposite to its contact with the said faces of its respective cylinder, for conducting fluid; and, means for driving said second shaft from said drive shaft at a less velocity, substantially as and for the purpose set forth.

LOYAL W. SHERIDAN.
